Richardson Company, Middletown, Ohio, a cor-
poration of Ohio

Application November 22, 1939, Serial No. 305,661

11 Claims. (Cl. 93—39.2)

This invention relates to containers and more particularly to containers formed from paper material or the like and having end closures.

The principal object of the invention is to provide a process for the continuous, high speed and quantity production of container bodies formed from blanks of paper material or the like and having an inwardly recessed shoulder adjacent the ends of the bodies providing for receiving end closures thereon.

A further object is to provide a simple and efficient process for cutting a plurality of blanks suitable for forming such container bodies from a web of paper material such as a relatively large sheet or roll of paper and for simultaneously winding the plurality of cut blanks into the form of the container bodies.

A further object of the invention is to provide a process for forming paper containers in which an inner portion of the body wall forms an inwardly recessed shoulder at one or both ends of the container body for receiving an end closure thereon and an outer portion of the body wall provides for securing the end closure in position on the shoulder.

A further object is the provision of apparatus providing for cutting a paper web into blanks of predetermined size and shape and for forming the blanks into container bodies of the character and in the manner hereinabove set forth.

A still further object is the provision of relatively simple and inexpensive apparatus for turning down the ends of the formed container bodies to provide for securing the end closures in proper position thereon.

Other objects and advantages will be apparent from the following description, the appended claims and the accompanying drawings, in which

Fig. 1 is an elevational view, partly diagrammatic, of a machine providing for cutting the container blanks and winding the same into the form of container bodies in accordance with the present invention;

Fig. 2 is a fragmentary plan view showing a portion of the paper web and a portion of the supporting table below the web and illustrating the manner in which the web is cut to provide the body blanks;

Fig. 3 is a fragmentary vertical section taken through one of the blank cutting knives and its cooperating die on the line 3—3 of Fig. 1;

Fig. 4 is a fragmentary vertical section taken through one of the blank cutting knives and its cooperating die on the line 4—4 of Fig. 1;

Fig. 5 is a part elevational part sectional view of an apparatus providing for turning down the ends of the formed container bodies to secure the end closures in proper positioning;

Fig. 6 is a fragmentary sectional view taken on the line 6—6 of Fig. 5;

Fig. 7 is a longitudinal sectional view through the container body at the completion of the forming operation and showing the closure member in position where it can be inserted in place;

Fig. 8 is a longitudinal sectional view showing a portion of the complete container with an end closure inserted and secured in position; and

Fig. 9 is a fragmentary longitudinal sectional view showing a modified end closure secured in position on the container body.

Referring to the drawings which illustrate a preferred embodiment of apparatus adapted to carry the invention into effect, there is shown a machine 10 which takes a web 11 of paper material, cuts the same into body blanks each having a portion of reduced width at the leading ends thereof, and winds the blanks into the form of convolute container bodies with the reduced portion of the blank forming the interconvolution of the body to provide inwardly recessed shoulders at the ends of the bodies. In the illustrated machine the paper web is supplied from a large jumbo roll 12 and has a width sufficient to provide a plurality of blanks arranged side by side, and the machine provides for simultaneously winding the plurality of blanks into convolute container form. The web 11 passes under a guide roll 13, and a pair of feed rolls 14 and 15 provide for unwinding the paper from the roll 12 and for feeding it to a pair of feed rolls 16 and 17 which rotate at the same peripheral speed as the rolls 14, 15. After a length of paper material sufficient to form a multi-wall tubular body of the desired diameter and number of convolutions has been fed forwardly the feeding operation terminates and a pair of cooperating shearing knives 20 and 21 operate to cut off the desired length of paper.

In the illustrated embodiment of the invention the web is cut into lengths suitable for forming convolute bodies having a wall comprising three complete turns plus a small overlap of the paper material, and when this severed length of paper has been fed forward by the rolls 16 and 17 the forward or leading end of the web 11 lies at the point marked "A" in Fig. 1 of the drawings, the trailing end being in feeding engagement with rolls 16, 17.

During the dwell of the paper web with the

leading end at the point "A," a plurality of longitudinally extending knives 25 operate on the leading portion of the web to cut a plurality of spaced elongated slots therein. The knives 25 are so arranged that when the cut-off length of paper web is subsequently slit into a plurality of individual body blanks as will be hereinafter described, the slotted or cut-away portions will be at the forward marginal edges of the individual blanks and provide a single portion of predetermined substantially uniformly reduced width at the leading end of each of the blanks, the remainder of the blanks being of substantially uniform full width providing for forming the body part and the extending end portions. Thus when the body blanks are wound into convolute container form the portions of reduced width at the leading ends of the blanks provide for forming inner recessed shoulders at the ends of the wound bodies.

Referring to Fig. 2 there is shown a portion of the paper web 11 immediately following the cut-off and slotting operations, and in this figure the lines 28 designate the leading end of the web, the line 29 designates the trailing end of a sheet which has just been severed by the cut-off knives 20 and 21, and the dashed lines 30 indicate the lines along which the web is to be subsequently slit to sever the web into the plurality of individual body blanks. As shown the slots 31 lie along the dashed lines 30 and since it is desired in the illustrated embodiment of the invention to provide inwardly recessed shoulders at both ends of the wound container body the knives 25 are so positioned that the slots are centered on the dash lines 30 and effect a reduction in the leading portions 32 of the body blanks by substantially equal amounts on each side thereof. The length of the slotting knives 25 is such that the slots 31 provide portions of reduced width 32 having a length sufficient to form an entire convolution of the container body when the blanks are wound into the container form. In the illustrated embodiment of the invention in which the body blanks have a length sufficient to provide three complete convolutions plus an overlap when wound into the container form, the length of the slots 31 will be approximately one-third the over-all length of the blanks.

As shown in Figs. 1, 3 and 4 the slotting knives 25 have a pair of cutting edges 35 and 36 which extend in spaced parallel relationship from the outer end of the knife to a point adjacent the handle portion 37 where they curve inwardly and upwardly as indicated at 38 and 39 and merge into a single cutting edge at the point 40. The curvature of the portions 38 and 39 is such that upon operation of the knives the inner ends of the slots 31 of the web 11 will be rounded as indicated at 41 in Fig. 2 to facilitate the folding over of the wider portions of the severed blanks during the subsequent spinning operation hereinafter described. The width of the knives 25 and hence the spacing between the cutting edges 35 and 36 is such as to provide the desired reduction in the width of the portions 32 of the blanks to cause the outer convolutions of the wound body to have sufficient length to be bent over and effectively secure the end closures in place on the internal shoulders provided by the reduced portions 32.

The slotting knives 25 cooperate with a plurality of cutting dies or blocks 44 which are inserted in the web supporting plate 45 of the machine 10 in proper positioning beneath each of

the slotting knives. As shown the plate 45 is provided with flanged openings for receiving the die blocks 44 and the dies are slotted as indicated at 47 to provide parallel cutting edges 48 and 49 which cooperate with the cutting edges 35 and 36 of the knives and curved cutting edges 50 and 51 which cooperate with the curved portions 38 and 39 of the slotting knives. Screws 52 provide for retaining the cutting dies 44 in position in the plate 45. The portions of the paper web which are removed by the slotting knives to provide the slots 31 drop through the slots 47 of the cutting dies 44 and may be removed from the machine by suitable means such as an endless belt. On either side of the paper web 11 it is only necessary to provide a slot that has one-half the width of the slots 31 as indicated at 53 in Fig. 2 and, accordingly, the outermost slotting knives 25 and cutting dies 44 at the outside edges 20 of the machine may be correspondingly modified so as to remove only the required amount of paper material from the side edges of the paper web.

Operation of the slotting knives 25 is effected by means of a cam member 56 which is mounted upon a shaft 57 and is provided with a grooved cam track 58 comprising a concentric portion 59 and an inwardly extending portion 60. The shaft 57 may comprise any suitable shaft of the drive mechanism for the machine which makes one complete revolution for each cycle of operation of the unwinding rolls 14 and 15 and the shearing knives 20 and 21. A bell crank 62 is pivotally mounted at 63 to a fixed portion of the machine frame and has an arm 64 provided with a roller 65 which is received within the cam groove 58 and an arm 66 which is pivotally connected at 67 to an upwardly extending link 68. The link 68 is pivotally connected at 69 to a crank arm 70 which is rigidly attached to a cross shaft 71 which carries the several slotting knives 25. The slotting knives 25 are rigidly attached to the cross shaft 71 so as to be operated in response to the rotation of the cross shaft. It will be evident from Fig. 1 that so long as the roller 65 travels in the concentric portion 59 of the cam groove 58 the slotting knives 25 will remain in the raised or inoperative position shown, but when the roller 65 enters the inwardly extending portion 60 of the cam groove the link 68 and crank arm 70 will be depressed by the bell crank 62 to cause rotation of the shaft 71 and operation of the slotting knives 25 to effect the slotting of the paper web. The slotting knives thus operate with a shearing action and progressively cut the paper web from the leading edge at "A" in Fig. 1 to the curved portions 41 at the inner ends of the slots. Immediately following the slotting operation the portion 60 of the cam groove returns the slotting knives to the raised or inoperative position. The angular positioning of the inwardly extending portion 60 of the cam groove 58 is such as to effect the slotting operation of the knives 25 in coordinated timed relation with respect to the machine as a whole and during the time that the paper web dwells for cut-off with its leading edge at the point "A" of Fig. 1 as above described.

Following operation of the cut-off knives 20 and 21 and the slotting knives 25, during which time the web remains stationary, the feed rolls 16 and 17 and another pair of feed rolls 14 and 15 resume operation and feed the cut-off length of paper material to a winding mandrel assembly indicated generally by the reference numeral

76. The unwinding rolls 14 and 15, however, continue to remain stationary for a further period of time sufficient to provide a desired spacing between the length of paper which has just been cut-off and the next length of paper, after which the rolls 14 and 15 resume operation to feed a new length of the web to the point "A."

As described above the cut-off and slotted length of paper web is slit through the slots 31 and along the dashed lines 30 of Fig. 2 to sever the web into a plurality of individual body blanks each having a portion of reduced width 32 at the leading end thereof. For this purpose a plurality of rotary cutters 77 cooperating with a roller 78 are spaced transversely of the machine intermediate the feed rolls 16 and 17 and the feed rolls 14 and 15 and provide for slitting the cut length of paper into the plurality of body blanks. A plurality of individual body blanks arranged side by side across the width of the machine are thus fed to the mandrel assembly 76 for winding simultaneously thereon into the form of multi-wall convolute container bodies having the portions 32 of reduced width innermost and towards the mandrel and forming the inner convolution of the wound body. The spacing between the rotary slitting knives 77 and thus the width of the blanks between the lines 30 of Fig. 2 is such as to provide for forming container bodies having a desired predetermined length or height.

The mandrel assembly 76 comprises a plurality of mandrels 80 carried by a suitable frame member diagrammatically indicated by the broken lines 81 and adapted to be intermittently rotated about a central shaft 82 to successively move each of the mandrels through a plurality of stations designated by the numerals 85, 86, 87, and 88 in Fig. 1 of the drawings. Station 85 comprises a winding station and it is here that the mandrel receives the plurality of body blanks as they are fed forwardly by the feed roll pairs 16, 17 and 74, 75 and winds the blanks into convolute container form. Suitable grippers 90 are provided on the mandrels for receiving the leading edge of the body blanks and retaining the same during the winding operation.

To provide for retaining the body in the wound form a pair of adhesive applying rolls 93 and 94 receive adhesive from a tank 95 and apply it to the body blanks during the winding of the blanks on the mandrel at the station 85, the roll 94 being actuated into adhesive transferring contact with the blanks on the mandrel at properly coordinated stages in the winding operation. The operation of the rolls 93 and 94 is preferably so controlled as to apply the adhesive between all overlapping surfaces of the body wall and throughout the entire length of the wound body including the portions of the outer convolutions which extend outwardly beyond the inner convolutions at the ends of the body. The roll 94 thus has a length or width sufficient to apply adhesive across the entire width of the body blanks including the wider portions thereof, and is preferably actuated into contact with the blanks as soon as the leading ends of the inner convolution come opposite the roll. During the application of adhesive to the reduced portions 32 of the body blanks the transfer of adhesive to the portions of the mandrel which are exposed by reason of removal of the slotted portions 31 of the blanks is prevented by the thickness of the paper web which maintains a suitable spacing between the roll 94 and the exposed portions of the mandrels. If desired, however, a

plurality of scrapers or the like positioned along the length of the roll 94 opposite the exposed portions of the mandrel may be actuated to scrape adhesive from the roll 94 during the application of the adhesive to the narrower portions of the blanks. In the preferred embodiment of the invention a label is applied to the outer surface of the wound body and to provide for adhesively securing the label in position on the body the contact between the adhesive applying roll 94 and the body blanks at the station 85 is preferably continued for at least one complete revolution of the mandrel after the winding of the bodies has been completed to effect the application of adhesive on the entire exterior surface of the wound bodies.

To effect the winding of the container bodies on the mandrel at the winding station 85 each of the mandrels is supported in the mandrel assembly frame for rotation about its own axis and a suitable means is provided at the winding station for effecting a predetermined rotation of the mandrel during its dwell thereat. Suitable means may also be provided for effecting a predetermined rotation of the mandrels about their own axes during dwell at one or more of the other stations such, for example, as the station 87 where a label is preferably applied to the adhesively coated outer surface of the formed bodies. The label preferably has a width corresponding to the entire extended length or height of the wound bodies so that when applied to the body it will extend entirely to the end edges of the outer convolution and cover the portions of the body wall that extend outwardly beyond the recessed shoulder of the inner convolution at either end of the body. After the bodies have been wound on the mandrel at the winding station 85 the mandrel assembly frame is intermittently rotated as described above to successively move the mandrel with the wound container bodies thereon through each of the stations 86, 87 and 88 and to successively move each of the other mandrels into the winding station 85 for the winding of container bodies thereon; it being understood that suitable means (not shown) is provided for effecting such indexing movement and dwell of the mandrels at the several stations in coordinated timed relation with the operation of the other portions of the machine.

The station 88 comprises a stripping station at which suitable means for freeing one end of the mandrels and effecting stripping of the wound container bodies therefrom are provided. During indexing movement and dwell of the mandrel assembly a continuous control is maintained over the angular positioning of each of the mandrels so that the seams of the container bodies will occupy predetermined positionings at the several stations and the grippers 43 will be in a proper position to receive a new supply of the container blanks when the mandrels are advanced into the winding station 85 following the stripping operation. A more detailed description of such mandrel assembly and its operation is contained in the patent to Scusa et al No. 2,163,318 and the copending application of Scusa Serial No. 250,477, filed January 12, 1939, both of which are assigned to the same assignee as the present invention, and to which reference is herein made for a more complete understanding of the machine and its operations.

When the container bodies are stripped from the mandrel of the forming machine 10 they will

have a form corresponding to that shown in Fig. 7 of the drawings in which the portion of reduced width 32 of the body blanks forms the inner convolution of the wound body and provides an internally recessed shoulder 100 at each end of the body and the outer convolutions 101 and 102 extend outwardly beyond the shoulder 100 at each end of the wound body. A label 103 is shown as secured to the outer surface of the outermost convolution 101 and as described above preferably extends over the full height of the outer convolution including the outwardly extending end portions as shown in Fig. 7. An end closure 105, Fig. 8, is then inserted in the open end of the container body and is seated upon the internal shoulders 100 provided by the inner convolution 32 of reduced height or length. The outwardly extending portions of the outer convolutions 101 and 102 together with the portion of the label secured thereto are then bent inwardly and downwardly to double back upon themselves as indicated at 106 in Fig. 9 to provide shoulders 107 and 108 which press against the outer side of the closure 105 and securely retain the closure in position on the internal shoulder 100. It will thus be evident that the end edge of the inner convolution 32 provides the shoulder 100 upon which the end closure 105 seats and that the end edges of the outer convolutions 101 and 102 of the wound body provide the shoulders 107 and 108 which press against the outer side of the end closure and retain it in position. The opposite end of the container body may be closed in a similar manner after the container has been filled with the desired contents.

To facilitate the spinning over of the outwardly extending end portions of the outer convolutions to fold the same back upon themselves and provide the shoulders 107 and 108 which bear against and secure the end closure in position on the inner recessed shoulder 100, the spinning operation is preferably effected prior to the complete setting of the adhesive securing the outer convolutions together and securing the label to the outmost convolution and while the adhesive is still in somewhat of a fluid state. The partially fluid adhesive on the outer convolutions operates to give these convolutions a certain amount of flexibility and extensibility whereby when the outwardly extending portions are folded over, the end edge 108 of the outer convolution 101 lies in substantially the same plane as the end edge 107 of the convolution 102 and bears against the closure member 105 to assist the shoulder 107 in securing the closure member in position. Any heat generated by friction during the spinning operation also tends to also facilitate the folding operation and lengthening of the outer convolution 101.

In Figs. 5 and 6 there is shown a preferred form of apparatus for effecting the folding of the outwardly extending convolutions of the wound container body to cause these portions to double or lap back upon themselves and provide the shoulder portions 107 and 108 which retain the closure for the container in proper positioning. Referring to these figures there is shown a spinning head 120 threaded on a spindle 121 adapted to be rotated by any suitable means not shown. A suitable chuck and mechanism, also not shown, is adapted to support the tubular container bodies and effect relative axial movement between the spinning head and the chuck to provide for effecting the bending operation and to cause separation of the parts for the insertion

and removal of the container bodies. As shown the spinning head 120 comprises a casting having a relatively deep circular groove 122 therein the outer diameter of which is substantially the same as the outer diameter of the container body so as to fit closely around the outer end of the tubular body and the inner diameter of which is such as to cause the folded-down portion of the container wall to double or lap back upon the adjacent portion of the body wall and be depressed tightly against this adjacent portion of the wall as shown in Fig. 8. To assist in guiding the end of the tubular container into the groove 122 when the spinning head and chuck are moved towards each other to effect the folding operation the outer edge of the groove is provided with a rounded bevel as indicated at 123 in Fig. 5.

The folding orlapping operation is effected by a plurality of dies 125 which are arranged radially of the axis of the spinning head 120 and extend entirely across the groove 122 adjacent the top portion 126 thereof. In the illustrated embodiment the dies 125 are in the form of elongated pins which extend through suitable openings or sockets 127 and 128 provided in the flange portion 129 and the body portion 130 of the spinning head, respectively, and have end portions 131 which extend radially outwardly from the flange 129. The portions of the pins 125 which are received within the openings 127 and 128 are of circular cross-section as indicated at 133 in Fig. 6 to permit rotation of the pins about the longitudinal axis thereof for a purpose to be hereinafter described, and the outwardly extending end portions 131 are provided with a flattened surface 134 to provide for effecting such rotation of the pin by the use of a suitable tool. The portion of each pin which extends across the groove 122 is provided with a slot 135 which extends transversely of the pins and in the direction of the groove. To provide for folding over the end of the container body when the spinning head with the dies therein is pressed against the body end the slots 135 are arcuate shaped in transverse cross-section as shown in Fig. 5 and form curved working surfaces 136 which extend from the outer wall 137 to the inner wall 138 of the groove 122. Thus as the rotating dies are pressed against the end of the container body the curved working surfaces 136 of the slots 135 cause the end wall portion of the body to bend over and downwardly and to be pressed against the adjacent body wall portion by the inner wall 138 of the groove.

As described above the dies or pins 125 are rotatable within the openings or sockets 127 and 128, and thus the angular positioning of the slots 135 about the axis of the pins may be adjusted. To prevent the edge of the slotted portions 135 of the dies 125 from cutting into the paper material upon rotation of the spinning head and also to facilitate and improve the folding operation of the dies the angular positioning of the pins 125 is so adjusted that the working surfaces 136 of the slots 135 extend at an angle to a plane normal to the axis of the spinning head as shown in Fig. 6 to thereby provide inclined or sloping surfaces which operate upon the end of the tubular body. The working surfaces 136 are thus arranged to extend at an angle with respect to the plane of the end edge of a tubular body adapted to be received within the groove 122, and as shown in Fig. 6 in which the direction of rotation of the spinning head and dies is indicated by the arrow the inclina-

tion or angularity of the working surfaces is such that the leading edge 140 of the slots inclines upwardly away from the end of a tubular body adapted to be received within the groove 122. The dies may be adjusted to any desired degree of slope or inclination of the working surfaces by rotating the pins 125 in the socket openings 127 and 128, and the pins are retained in the desired adjusted positioning by means of set screws 141 which thread into the spinning head 120 and engage the pins 125. The set screws 141 also prevent the dies 125 from working outwardly of the spinning head and maintain the slots 135 in proper positioning with respect to the groove 122 of the spinning head.

In Fig. 9 of the drawings there is shown a modified form of the invention in which the end closure 150 comprises a cup-shaped member having upwardly extending side flanges 151. The cup-shaped closure 150 rests upon the shoulder 152 provided by the inner convolution 153 of reduced length with the flanges 151 extending towards the outer end of the container body. The outer convolutions 154 and 155 are then folded over and pressed back against the side flange 151 of the closure and provide shoulders 156 and 157 which press against the bottom of the cup-shaped closure 150 and retain the closure in position on the internal shoulder 152.

While the methods, forms of apparatus, and articles herein described constitute preferred embodiments of the invention, it is to be understood that the invention is not limited to these precise methods, forms of apparatus, and articles, and that changes may be made therein without departing from the scope of the invention which is defined in the appended claims.

What is claimed is:

1. A process of the character described for forming from paper material or the like multi-wall convolutely wound containers having end closures inwardly recessed thereon comprising the steps of feeding a web of paper material having a width sufficient for forming a plurality of body blanks arranged side by side and a length sufficient for forming an inner and a plurality of outer convolutions of the wound container body, cutting said web to provide a plurality of elongated transversely spaced slots in the forward end of the web, slitting said web through said slots to provide a plurality of body blanks each having a slotted portion at a side edge thereof, said slots providing a portion of reduced width in the leading end of each of said blanks which forms the inner convolution, said portion of reduced width having a length sufficient to form said inner convolution of the wound container body, winding said blanks into convolute container form with said portions of reduced width on the inside to form container bodies having an inner recessed shoulder at an end of the bodies adapted to receive an end closure thereon, adhesively securing said bodies in wound form with the adhesive extending to the end edges of the outer convolutions, inserting a closure member in said end of the bodies to seat on said recessed shoulder, and spinning the outwardly extending portions of the outer convolutions prior to complete setting of said adhesive to fold the end edges of said portions into retaining engagement with said closure member.

2. A process of the character described for forming from paper material or the like multi-wall convolutely wound containers having end

5 closures inwardly recessed thereon comprising the steps of intermittently feeding blanks of paper material having a size suitable for winding into the form of said multi-wall convolute container bodies and a length sufficient for forming an inner and a plurality of outer convolutions of the wound container body, operating upon said body blanks with a shearing action during period of dwell of said feed means to cut away a portion of the paper material at a side edge of the forward part of the body blanks to provide a portion of reduced width at the leading ends of the blanks which forms the inner convolution, said portion of reduced width having a length sufficient to form said inner convolution of the wound container body, winding said blanks into convolute container form with said portion of reduced width on the inside to form container bodies each having an inner recessed shoulder at an end of the formed bodies adapted to receive an end closure thereon, adhesively securing said bodies in wound form with the adhesive extending to the end edges of the outer convolutions, inserting a closure member in said end of the bodies to seat on said recessed shoulder, and operating upon the outwardly extending portions of the outer convolutions prior to complete setting of said adhesive with guiding and forming surfaces inclined with respect to the end edge of the bodies to fold the end edges of said portions of the outer convolutions into retaining engagement with said closure member.

3. In a process of the character described for forming container bodies from paper material or the like in which a web of paper material having a width sufficient for forming a plurality of container bodies is slit into a plurality of body blanks arranged side by side and said plurality of blanks are wound on a mandrel into the form of multi-wall convolute container bodies, the steps which comprise cutting said web to provide a plurality of spaced elongated slots positioned to lie along a part of the marginal edge of each of said blanks at the forward ends thereof to thereby provide a portion of reduced width in the leading ends of the blanks, said portion of reduced width having a length sufficient to form an inner convolution of the wound container body, and winding said plurality of blanks simultaneously on said mandrel into convolute container form with said reduced portion inwardly and next to the mandrel to provide container bodies having an inner convolution having a recessed shoulder adapted to receive an end closure thereon.

4. In an apparatus of the character described for forming container bodies from paper material or the like in which a web of paper material having a width sufficient for forming a plurality of container bodies is slit into a plurality of body blanks arranged side by side and said plurality of blanks are wound on a mandrel into the form of multi-wall convolute container bodies, the combination of means for cutting said web to provide a plurality of spaced elongated slots positioned to lie along a part of the marginal edge of each of said blanks at the forward ends thereof to thereby provide a portion of reduced width in the leading ends of the blanks, said portion of reduced width having a length sufficient to form an inner convolution of the wound container body, and means for winding said plurality of blanks simultaneously on said mandrel into convolute container form with said reduced portion inwardly and next to the mandrel to provide

container bodies having an inner convolution having a recessed shoulder adapted to receive an end closure thereon.

5. An apparatus of the character described for forming from paper material or the like multi-wall convolutely wound container bodies adapted to receive end closures inwardly recessed thereon comprising means for feeding a web of paper material having a width sufficient for forming a plurality of body blanks arranged side by side, means for cutting said paper web to simultaneously provide a plurality of body blanks each having a forward marginal portion cut away to provide a portion of reduced width at the leading ends of the blanks, said blanks having a length providing for forming a plurality of convolutions when wound into container form and said portion of reduced width having a length sufficient to form at least one convolution of the wound container body, and means for winding said cut blanks simultaneously into convolute container form with said portion of reduced width on the inside to simultaneously form a plurality of container bodies each having an inner convolution of less length than an outer convolution to thereby provide an inner recessed shoulder at an end of the formed bodies.

6. An apparatus of the character described for forming from paper material or the like multi-wall convolutely wound container bodies adapted to receive end closures inwardly recessed thereon comprising means for feeding blanks of paper material having a size suitable for winding into the form of said multi-wall convolute container bodies, means coordinated with the operation of said feed means for cutting away a portion of the paper material at a forward marginal side of said body blanks to provide a portion of substantially uniformly reduced width at the leading ends of the blanks, said portion of reduced width having a length sufficient to form at least one convolution of the wound container body and the remainder of said blanks having a substantially uniform greater width and a length sufficient to form a plurality of additional convolutions, means for winding said blanks into convolute container form with said portion of reduced width on the inside to form container bodies each having an inner recessed shoulder at an end of the formed bodies, and means effective for applying adhesive across the entire width of said blanks including the wider portion thereof to adhesively secure the bodies in wound form and provide adhesive on the portions of the body wall outwardly of said recessed shoulder.

7. An apparatus of the character described for forming from a jumbo roll of paper material or the like multi-wall convolutely wound container bodies adapted to receive end closures inwardly recessed thereon comprising means for intermittently unwinding and feeding a web of paper material from said jumbo roll, means for cutting said web into body blanks, means for operating upon said web with a shearing action during dwell of said unwinding and feeding operations to effect a substantially uniform reduction in width of a portion of the body blanks at the leading ends thereof, said blanks having a length providing for forming a plurality of convolutions when wound into container form and said portions of reduced width having a length sufficient to form at least one convolution of the wound container body, and means for winding said cut blanks into convolute container form with said portions of reduced width on the inside to pro-

vide container bodies having an inner convolution having a recessed shoulder adapted to receive an end closure thereon.

8. An apparatus of the character described for forming container bodies from paper material or the like comprising means for intermittently feeding a blank of paper material having a size suitable for winding into the form of multi-wall convolutely wound container bodies, means for operating upon said web with a shearing action during dwell of said feeding operation to simultaneously provide a cut-away portion at each of the forward marginal sides of each of said blanks to thereby provide a portion having its width substantially uniformly reduced at both sides of the leading ends of the blanks, said portion of reduced width having a length sufficient to form at least one convolution of the wound container body, and mandrel means for winding said blanks into convolute container form with said reduced portions next to the mandrel to form container bodies having an inner convolution with a recessed shoulder adapted to receive an end closure thereon at each end of the wound body.

9. An apparatus of the character described for forming from paper material or the like container bodies adapted to receive end closures inwardly recessed thereon comprising means for feeding blanks of paper material having a size suitable for winding into the form of a multi-wall convolutely wound container bodies, mandrel means for receiving said blanks and winding the same into the form of said multi-wall convolute container bodies, means including an elongated shearing knife positioned in a plane extending substantially parallel with the direction of feed of said blanks for cutting an elongated slot in said blanks adjacent a side edge thereof to provide a portion on said blanks of reduced width, and means coordinated with the operation of said feed means for effecting operation of said shearing knife to provide said portion of reduced width at the leading end of said blanks and of a predetermined length sufficient to form an inner convolution of the wound container bodies to thereby provide for winding container bodies having a recessed inner shoulder at an end of the wound body.

10. An apparatus of the character described for forming from paper material or the like container bodies adapted to receive end closures inwardly recessed thereon comprising means for intermittently feeding blanks of paper material having a size suitable for winding into the form of multi-wall convolute container bodies, mandrel means for receiving said blanks and winding the same into the form of said multi-wall convolute container bodies, means including an elongated shearing knife positioned in a plane extending substantially parallel with the direction of feed of said blanks for cutting an elongated slot of predetermined length in said blanks adjacent a side edge thereof to provide a portion on said blanks of reduced width, and means coordinated with the operation of said feed means and operable during periods of dwell of said feeding means for effecting operation of said shearing knife to provide said portion of reduced width at the leading ends of said blanks, said portion of reduced width having a length sufficient to form an inner convolution of the wound container bodies to thereby provide for winding container bodies having a recessed inner shoulder at an end of the wound body.

11. An apparatus of the character described

for forming from paper material or the like container bodies adapted to receive end closures inwardly recessed thereon comprising means for feeding blanks of paper material having a size suitable for winding into the form of multi-wall convolute container bodies, mandrel means for receiving said blanks and winding the same into the form of said multi-wall convolute container bodies, a cross-shaft extending substantially transversely to the direction of feed of said blanks, a plurality of elongated shearing knives mounted on said cross-shaft and extending in planes substantially parallel with the direction of feed of the blanks, said shearing knives providing for cutting elongated slots of predetermined

15

length in said blanks adjacent the side edges thereof to provide a portion of reduced width on the blanks, and means coordinated with the operation of said feed means for effecting rotation of said cross-shaft and operation of said shearing knives to provide said portion of reduced width at the leading ends of said blanks, said portion of reduced width having a length sufficient to form an inner convolution of the wound container bodies to thereby provide container bodies having recessed inner shoulders at the ends thereof.
